UNITED STATES PATENT OFFICE.

ALLEN HOWARD MIX, OF BURLINGTON, VERMONT, ASSIGNOR TO PORTER SCREEN MANUFACTURING COMPANY, OF BURLINGTON, VERMONT.

SASH-HOLDER.

No. 911,515.

Specification of Letters Patent.

Patented Feb. 2, 1909.

Application filed November 9, 1908. Serial No. 461,731.

To all whom it may concern:

Be it known that I, ALLEN HOWARD MIX, of Burlington, in the county of Chittenden and State of Vermont, have invented a new 5 and useful Improvement in Sash-Holders, of which the following is a specification.

My invention relates to that kind of window screen which is adapted to slide up and down between guides on the window frame, 10 and is provided for this purpose on its vertical edges with outwardly spring pressed rollers which adapt themselves to slight inequalities and variations in width of the window frame to which they are fitted and 15 at the same time, by reducing friction, facilitate the raising and lowering of the screen.

My improvement has to do with means for holding the screen in elevated position in the position to which it may be raised without, 20 however, locking it in that position or holding it there so tightly that it may not be lowered by simply pressing or pulling down on the screen frame, and it consists in a simple and effective device for this purpose, 25 the novel features and characteristics of which will first be described in connection with the accompanying drawings and will then be more particularly pointed out in the claim.

30 In the drawings—Figure 1 is a front elevation of a screen and associated parts of the window frame and guides embodying my invention, the screen being in lowered position and the lower spring pressed roller device at the left of the screen being shown in vertical section. Fig. 2 is a like section on enlarged scale of said roller device in the 35 position it occupies when the screen is elevated far enough to bring the same into engagement with the holding or retaining recess in the guide. Fig. 3 is a cross section on line 3—3, Fig. 1. Fig. 4 is a cross section on line 4—4, Fig. 2. Fig. 5 is a perspective view of a portion of one of the vertical side 40 bars of the screen frame together with that portion of its associated guide rail in which the retaining recess is formed.

In the drawings A (Fig. 1) is a screen of any approved construction which is adapted 50 to move between guides B, on the opposite vertical faces of the window frame to which the screen is applied, and is provided with any approved spring pressed roller devices to move in the guides. There will be 55 usually two of such outwardly spring

pressed roller devices contained in recesses in the outer edge of each vertical bar of the screen frame, and the rollers will project so as to bear against the guides, and preferably to enter vertical guide grooves formed 60 in the same. Suitable retracting devices, typified at R (Fig. 5) may be attached to the free end of the roller brackets or carriers, so as to manually retract the rollers within their recesses whenever it is desired to fit 65 the screen to, or withdraw it from, the guides.

Having reference now more particularly to Figs. 1-4, each spring pressed roller device in the present instance consists of a 70 sheet metal bracket or carrier c in which is mounted a roller d. The bracket or carrier is located in a recess e in the frame, where it is secured by a screw or other suitable fastener passing through its lower flexible end 75 c', into the frame. This flexible end permits the bracket to move in and out as it would if there were a hinge. Any suitable form of hinge indeed can be used for this purpose. The upper free end c² of the 80 bracket is spring pressed outwardly by a spirally coiled spring f which is confined between c² and the bottom of the recess e. A retractor R which limits the extent to which the roller can be pressed outwardly, and 85 which can be used also to manually retract the roller as desired, is connected to the roller bracket by its stem r which extends through an opening in the frame and through the coiled spring f to the free end c² 90 of the bracket to which it is suitably secured. The guide B is of L shape in cross section, and has in its face adjoining the roller bearing face of the screen frame a longitudinal groove b which the rollers on that 95 side of the screen enter—bearing normally against the bottom of the same.

Thus far there is nothing essentially new in the construction. I come now to those features which embody my improvement, 100 which consists in the provision of a holding member on the roller bracket or carrier, in conjunction with a retaining recess located at a suitable point in the guide, to permit the roller, when the screen has been raised 105 to the desired height, to move forward, or outward, into the recess far enough to allow the holding member on the roller carrier or bracket to enter the retaining recess and engage the retaining surfaces therein— 110

these surfaces, as well as those of the holding member which engage it, being so inclined as to hold only by friction, which is not sufficient to prevent the screen frame 5 from being lowered by the application of sufficient downward pull or pressure thereon.

The holding member on the roller bracket consists in this instance of two rounded projections *g* on the face of the bracket, one on 10 each side of the roller. The retaining recess in the guide consists of two shallow concave portions *h*, and a deeper central concave portion *h'* between the two shallower portions, to receive the roller. The parts 15 are so proportioned that when the roller moves in its groove in the unrecessed portion of the face of the guide, it will bear against the bottom of the groove while the projections *g* are held out of contact with 20 the face of the guide, as illustrated in Figs. 1 and 3. But when the recess is reached, the central portion *h'* of it which will be entered by the roller is of such depth that the holding projections *g* are permitted to enter 25 and fit into and against the shallower portions *h* of said recesses, thus establishing a frictional contact which will hold the screen in its elevated position. As, however, there 30 are no abrupt corners to the projections *g* and the several portions of the retaining recess, downward pull or pressure on the screen frame will move it down until the roller once more takes its bearing against the 35 guide, when the projections *g* will be again lifted from frictional contact with the guide.

It will usually be sufficient to provide one retaining recess in each guide, so that one roller bracket on each side of the frame can

be used as a holding member. Of course the roller brackets—all four of them—may be 40 of like construction; for it is only when a proper recess is provided at the proper point in the guide that any holding member on any one of the brackets is ever called into action.

Having described my improvement and the best way known to me of carrying the same into effect I state in conclusion that I do not limit myself to the precise structural details hereinbefore set forth in illustration 45 50 of my invention, since manifestly the same can be varied in a number of particulars without departure from the spirit of the invention: but

What I claim as new and desire to secure 55 by Letters Patent is as follows:

In combination with the screen frame, an outwardly spring pressed roller bracket or carrier located in a recess in said frame, and a roller mounted in said carrier, of a holding member on and projecting from the outer face of the carrier, a guide against which the roller normally bears so as to relieve the holding member from frictional contact with said guide, and a retaining recess in the 60 65 guide having a shallower portion to receive and frictionally engage the holding member, and a deeper portion to receive the roller, substantially as and for the purposes hereinbefore set forth.

In testimony whereof I affix my signature in presence of two witnesses.

ALLEN HOWARD MIX.
